US0D1092747S

(12) United States Design Patent (10) Patent No.: US D1,092,747 S
(45) Date of Patent:  Sep. 9, 2025

(54) DENTAL INSTRUMENT

(71) Applicant: Aleksander Orzelowski, Pabianice (PL)

(72) Inventor: Grzegorz Wasik, Lódz (PL)

() Term: 15 Years

(21) Appl. No.: 35/522,259

(22) Filed: Aug. 20, 2024

(80) Hague Agreement Data

Int. Filing Date: Aug. 20, 2024

Int. Reg. No.: DM/239782

Int. Reg. Date: Aug. 20, 2024

Int. Reg. Pub. Date: Sep. 13, 2024

(51) LOC (15) Cl. 24-01

(52) U.S. Cl.

USPC D24/176

(58) Field of Classification Search

USPC D24/176, 177, 178, 179, 180, 181, 182

CPC A61G 15/16; A61C 1/0007; A61C 19/00

See application file for complete search history.

Primary Examiner — Mary Shannon Malley

(57) CLAIM

The ornamental design for dental instrument as shown and described.

DESCRIPTION

3. Dental instrument
4. Dental instrument
5. Dental instrument
6. Dental instrument
3.1: Top
3.2: Left
3.3: Bottom
3.4: Front
3.5: Right
3.6: Back
3.7: Perspective

4.1: Top
4.2: Left
4.3: Bottom
4.4: Front
4.5: Right
4.6: Back
4.7: Perspective
5.1: Top
5.2: Left
5.3: Bottom
5.4: Front
5.5: Right
5.6: Back
5.7: Perspective
6.1: Top
6.2: Left
6.3: Bottom
6.4: Front
6.5: Right
6.6: Back
6.7: Perspective

1 Claim, 28 Drawing Sheets
